Attns.

UNITED STATES PATENT OFFICE.

HERBERT H. BUFFUM, OF LACONIA, NEW HAMPSHIRE.

SPRINKLER-HEAD.

1,273,818.

Specification of Letters Patent. Patented July 30, 1918.

Application filed February 1, 1918. Serial No. 214,818.

To all whom it may concern:

Be it known that I, HERBERT H. BUFFUM, a citizen of the United States, and resident of Laconia, in the county of Belknap, State 5 of New Hampshire, have invented an Improvement in Sprinkler-Heads, of which the following description, in connection with the accompanying drawings, is a specification, like characters on the drawings representing like parts.

This invention relates to sprinkler heads such, for example, as are used in automatic fire extinguishing systems and the object is to provide a device of cheap and simple 15 construction and one which may readily be assembled.

My invention will best be understood by reference to the following description of the illustrative embodiment thereof shown in 20 the accompanying drawings wherein:—

Figure 1 is a side elevation of a sprinkler head with part cut away; and

Fig. 2 is a front elevation thereof as seen from the left of Fig. 1.

I have herein disclosed my invention (Fig. 1) as applied to a sprinkler head of that type wherein a valve 3 is held over the outlet of a fitting 5 by means of a strut, herein denoted generally by the numeral 7, 30 interposed between the valve and an opposed abutment 9. The abutment may, as in the present instance, be formed as a part of a resilient yoke 11 (see Fig. 2).

While the strut may take various forms, 35 I have here illustrated one which comprises two bell-crank levers which have the substantially counterpart arms 13 and 15 respectively, pivotally engaging abutment and valve respectively and (herein through 40 immediate means presently to be described) having a pivotal engagement with each other. The point of bearing between the two arms is out of the line of stress between the two 45 points of bearing on valve and abutment and thus the two arms are each adapted to serve as a brace between the parts, disposed obliquely to the line of stress between them. In other words, in the form shown the arms 50 co-operatively form a toggle partially broken and the pressure thereon of the valve and abutment tends further to break the toggle. To maintain the toggle against any water pressure that may be behind the valve and against the spring pressure of the yoke 11, 55 the levers have other arms 17 and 19 extending laterally therefrom, which may be con-

nected by a thermally releasable device 21 normally holding the two arms 13 and 15 in the positions shown and thus maintaining the valve. The device 21 may be and preferably is, as here illustrated, of the form shown in my Patent No. 1,255,111, embodying a set of plates normally held together by readily fusible alloy to provide a tension link. The parts are assembled as shown in Fig. 1 and preferably the proportion is such that the resilient yoke 11 is somewhat sprung. The point of bearing between the two arms 13 and 15 is at one side of the line of stress extending between the points of bearing of those arms on valve and abutment and thus the resilient pressure of the yoke 11 and any water pressure that may be behind the valve 3 tends to break the toggle joint formed by these arms. This tendency is resisted by the device 21 but when on an undue rise of temperature the device is released, the two arms will rock on each other and on the valve and abutment and the strut will be dismembered and withdrawn from between the valve and abutment, thereby releasing water through the former.

The structures as so far described, including the particular exemplary form of strut, are not novel to this application. My invention more particularly contemplates the provision of means for tensioning the strut between the valve 3 and the abutment 9, thereby firmly to hold the former on its seat and to apply suitable tension to the resilient yoke 11 whereby it will act to dismember the strut when the device 21 is released.

In the embodiment of the invention here illustrated I provide for a proper tensioning of the strut member 7 by means of a key 23 which is here shown as interposed between the two bell crank lever members. Referring to Fig. 2, the key may consist of a thin plate of metal fitting into suitable slots in the opposed ends of the arms 13 and 15. Preferably it has one straight edge 25 which is rounded and engages in a correspondingly rounded groove, thus providing a fulcrum between the piece 23 and the arm 13. The opposite edge 27 is sloping and is adapted to co-operate with the oppositely sloping bottom of a groove in the arm 15. When in position the key 23 will act as a unit with the arm 15, the arm 13 turning thereon when the sprinkler head operates.

It will be apparent from an inspection of Fig. 2 that if the member 23 is moved to

the left, viewing that figure, the sloping surface 27 will wedge the two arms 13 and 15 apart and press apart the valve 3 and abutment 9. Conveniently the key is made of considerable length and when the parts are assembled it may be pressed along in the grooves in the two opposed faces of the lever members until suitable tension is attained and any projecting portions thereof can be trimmed off to provide a structure appearing substantially like that shown in Fig. 2.

Prior to my present invention it has been customary to provide sprinkler heads of this type with a screw passing through the abutment 9 which was set up to provide suitable tension upon the strut, such for example as the type of strut here shown. My present invention does away with this screw, cheapening the cost of the sprinkler and considerably diminishing the number of operations necessary to the assembling of the same. Furthermore, the upper portion of the yoke 11 which provides the abutment need not be enlarged to permit the passage of the screw 25 and thus the distributor 29 is not masked in any way. This distributor 29 may be applied as shown by burring over a portion of the yoke thereon.

Having thus described in detail my invention as applied to the particular type of strut chosen for illustration in the drawings as an example, what I claim as new and desire to secure by Letters Patent is:—

1. A sprinkler head comprising a valve, an opposed resiliently yieldable abutment, an interposed strut comprising a pair of toggle members having extending arms, a thermally releasable connection between said arms and a key between said members having pivotal engagement with one and wedging engagement with the other.

2. A sprinkler head having a valve retaining strut comprising two members arranged for relative pivoting on the release of the head and means to tension the strut comprising a key interposed between said members having pivotal engagement with one and wedging engagement with the other.

3. A sprinkler head having a valve retaining strut comprising a member normally held in retaining position by a thermally releasable retaining device and arranged to

rock free on release thereof and a strut tensioning means comprising an element engaging said member and having a straight edge 55 providing a rocking bearing and an opposed inclined edge.

4. In a sprinkler head of the type wherein in a strut is interposed between a valve and an abutment, a member having an arm disposed obliquely to the line of stress between valve and abutment and located as a brace to retain the valve and another arm extending angularly from the first, a thermally releasable device engaging said other arm for holding said member and a wedge for tensioning the brace.

5. A sprinkler head comprising a valve, an opposed abutment and an interposed strut comprising toggle levers, fusible means resisting movement of the toggle and a wedge engaging one of the levers to apply endwise tension to the toggle.

6. A sprinkler head comprising a valve, an opposed abutment and an interposed strut including a brace disposed obliquely to the line of stress between valve and abutment, thermally releasable positioning means therefor and means to tension the brace between the valve and abutment, which means provides a pivotal bearing for the brace and includes two parts having coöperating oppositely sloping surfaces.

7. A sprinkler head comprising a valve, an opposed abutment, and a multipartite interposed strut having a bearing between two parts thereof out of the line of stress between said valve and abutment and thermally releasable means for holding the parts from dismemberment, two parts of said strut 90 having coöperating, transverse, oppositely sloping surfaces.

8. A sprinkler head comprising a valve, an opposed abutment and an interposed strut including a member having a pivotal bearing in the line of stress, another member in coöperation therewith tending to swing said first member about said bearing, thermally releasable means opposing such movement and means for tensioning said strut including a transverse wedge.

In testimony whereof I have signed my name to this specification.

HERBERT H. BUFFUM.
